COTTON PICKING MACHINE

William Neal Smith, Dallas, Tex.

Application November 12, 1940, Serial No. 365,289

6 Claims. (Cl. 56—41)

This invention relates to cotton harvesting and picking machines and it has particular reference to that type or kind of cotton picking machine wherein a series of reciprocating needles or gathering units are provided to engage the stalks bearing the cotton and so constructed that the lint will readily adhere to or be entwined about the needles in such manner as to withdraw the cotton from the open bolls and deposit the same into a receptacle suited for the purpose and the principal object of the invention resides in the provision of a new and novel mechanical arrangement and assembly of elements for imparting to the gathering units or needles a certain desirable movement by which they are rendered more effective in their performance as stated, in engaging, withdrawing and releasing the cotton into containers for disposal in any suitable manner.

Still another object of the invention resides in a comparatively simple mechanical arrangement for imparting rotary motion to the several groups of picking needles as they enter the foliage of the stalk to perform the improved function desired.

Another object of the invention resides in the provision, as stated, of a novel mechanical arrangement for operating the picking units or needles in groups, of which there are several as a unitary structure opposing the rows of cotton, the said groups of picking units being capable of alternate reciprocative movement, so that each stalk of cotton or bush will be subjected to the full effects of the opposing groups of reciprocating and rotating needles.

It is intended, as one of the outstanding features of the invention, that the picking needles, while collectively advanced into the stalk foliage in groups, each group will alternate as expressed but the needle assemblies are each provided with means to impart rotation thereto during the effective thrust or picking movement, becoming inoperative on the retracting movement of the needle so that the latter will not rotate, and will be relieved of its cotton by contact with a stripper head so disposed in a compartment of the machine that a suitable air suction will remove the cotton to a receptacle in the machine designed to receive the same.

Another object of the invention is to provide, together with the novel needle operating device, an improved structure in the needle itself and in which the end of the needle entering the stalk foliage has a diameter slightly greater than the distance between the tips of the teeth disposed

in opposed relationship on the needles, whereby to protect the stalk, unopened bolls, squares and the like from any injurious effects the teeth may have thereon when entering the foliage, since to bruise the bark of the stalk would result in releasing the sap which would likely adhere to the cotton rendering it most difficult to handle.

With the foregoing and other objects as paramount, the invention has particular reference to its salient features of construction and arrangement of parts to become manifest as the description proceeds, taken in connection with the accompanying drawing, wherein:

Figure 1 is a side elevational view of a picking box unit, showing one group of picking assemblies.

Figure 2 is a view in longitudinal section showing the improved needle and operating means therefor.

Figure 3 is a detail view of the operator section of a needle.

Figure 4 is a transverse section on line 4—4 on Figure 3.

Figure 5 is a detail view of the picking spindle section.

Figure 6 is a transverse section on line 6—6 on Figure 5.

Figure 7 is a fragmentary view, in longitudinal section, of the spindle sleeve.

Figure 8 is an enlarged fragmentary detail view of Figure 2, taken on line 8—8 thereon, and

Figure 9 is a fragmentary detail view on line 9—9 on Figure 8.

In continuing further and in greater detail with the drawing, it is pointed out that invention resides especially in the construction of the picking needle and the means by which it is caused to revolve during the picking action, to become non-rotatable as it is retracted and the invention is not concerned with any specific form of machine construction or driving means. However, the following description will include a form of reciprocating means for the groups or banks of picking units in order that a complete understanding of the invention may be had.

In Figure 1 is shown a picker box assembly, shown in side elevation and generally referred to by reference numeral 10, and wherein is disposed a group of needle assemblies of the invention. These assemblies are arranged in pairs, one being situated on either side of a row of cotton so that certain of the groups of needles will enter the plant during withdrawal therefrom of other groups.

In the box 10 a vertically disposed face plate

11 is provided and which serves as a mounting for the needle assemblies. Since each assembly of each group is the same, it will be considered sufficient to describe a single needle assembly as representative of the entire group.

A picking spindle sleeve 12 is secured at its forward end in an aperture in the face plate 11 provided therefor by means of nuts 13 which, in conjunction with a shoulder *a* in the sleeve 12 and key 13^a, hold the sleeve against longitudinal and rotative displacement with respect to the face plate 11.

The picker spindle, which operates in the sleeve 12 is in two axially aligned sections, the rear or rotator end being identified by numeral 14 while the picker stem is identified by numeral 15, shown in detail in Figures 3 and 5 respectively. The rotator section of the picker spindle is in part, square in transverse cross-section (Figure 4), so that when each end is secured and the body twisted in opposite directions, the result produces the characteristic of a helical groove *b*. The inner end portion *c* is machined to provide a shaft while the opposed end *d* is threaded to be received in a coupling block 16, which block serves the dual function of holding the spindle sections in end to end relationship and to afford a means for locking the spindle for rotative movement in one direction and to which specific reference will be made presently.

Surrounding the picker stem 15, within the end of sleeve 12, so that it will bear against a thrust washer 17 is an "oilless" bearing 18. This bearing is held in position by means of a retaining means 19 which will be herein referred to as the stripper as it likewise serves to remove cotton impaled on the needles. The picker stem 15 of the needle reciprocates in the bearing 18.

Mounted for sliding movement on the rear end of sleeve 12 is a second sleeve or collar 20. The interior of this collar has an annular shoulder *e* and from this point rearwardly, the inner diameter of the collar is greater than from the shoulder forward, in order to provide a recess for balls 21, reposing in recesses 22 (Figure 7) in the inner end of sleeve 12. The sleeve 12 is also provided with slots 23 through which extend inwardly bolts 24 which may also be referred to as "closing dogs" inasmuch as their presence in the assembly is to cause the balls 21 to converge on the helical surface *b* of the spindle section 14 to cause the spindle to rotate, as will be explained fully presently.

The inner end or shaft *c* of the picker spindle passes through a thrust bearing assembly, made up of an outer bushing 25 and a concentrically arranged inner bushing 26, each having flanges 27, spaced apart, to receive the ball race 28. The bushings extend through an aperture in an actuating bar 29, which bar is vertically disposed in the box or housing 10 to accommodate a group of picker assemblies, as shown in Figure 1. A thrust pin 30 is arranged for longitudinal movement below and in parallel relationship with each spindle and a thrust washer 31 is held in position by a nut 32 to hold the washer in position to engage the thrust pin, to bear against and move the collar 20 through the bearing assembly 28. A lug 28^a integral with the washer has an oblique face which will permit rotation of the washer and consequently the spindle in one direction but will not slide over pin 30 upon a tendency of the spindle to rotate in the opposite direction or retracting movement.

It is understood that the actuating bar 29 is 75

reciprocated in a horizontal plane to cause the picker spindles to be thrust forward into the cotton plants with a rotary motion and retracted without rotary movement. To accomplish such movement of the actuating bar, a pair of eccentrics 33, are mounted each upon a shaft 34 and are provided with arms 35, pivotally connected at 36 to links 37, which links are pivotally joined together at 38. To the extremity of each link 10 37 is pivoted connecting links 39 at *f*, the opposite ends of the links being pivoted to the upper and lower ends of the actuating bar 29 at *g*.

It is apparent from the foregoing that as the shafts 34 are revolved, the eccentrics 33 will 15 oscillate to effect a change in the positions of the links 37 and 39, having the effect to reciprocate the actuating bar 29. Rollers 40, journaled in the ends of the actuating bar operate in channels 41 in the top and bottom of housing 10 to maintain strict rectilinear movement of the picking spindles, the ends of which are secured, as stated, to the actuating bar.

In operation: At the end of the forward movement of the actuating bar 29 and spindle the 25 thrust washer 31 bears against the thrust pin 30, which, in turn, pushes against the collar 20 urging the same forward on sleeve 12. Due to this action, the balls 21, which were reposing in the helical grooves *b* of the spindle section 30 14, will be caused to recede therefrom into the annular cavity of collar 20. This operation takes place immediately at the start of the rearward movement of the spindles and consequently they do not rotate during such rearward movement.

35 Immediately before the rearward movement is reached, the block 16, by which the two sections of the spindle are coupled together, engages the dogs or inwardly directed bolts 24, thereby urging the collar 20 rearwardly, pushing the shoulder *e* of the collar against the balls 21, causing them to advance upon the portion 14 of the spindle, to lie in the groove *b* therein, preparatory to rotating the spindle upon the next forward thrust. It is apparent therefore, that with the balls in contiguous relation to the surface *b* of the spindle section 14, forward movement of actuating bar 29 will cause the spindle to travel axially through the sleeve and rotation will be imparted thereto by reason of the relative position of the balls 21 thereto.

50 Returning to the specific construction of the needles, it is pointed out that while the barbs or teeth *h* thereof are not unlike those of the needles employed in analogous machines but attention is directed to the fact that the needle design of the present invention embraces an integral disc 42 whose diameter, as stated, exceeds slightly the overall width of the needle stem 15 and when rapidly rotated, assumes the appearance of a ball. This feature insures against damage to the foliage, bolls and squares or the stalk.

55 As the spindle is withdrawn into the sleeve 12, the picker section 15 is likewise withdrawn through apertures 43 in a front plate 44 at the operative side of the box 10 next adjacent the cotton row and as the spindle is thus moved, such cotton as has been entwined about the picker end, will be wiped off by contact with the stripper head 19, and the cotton will be instantly caught up by air suction through chamber C of the box 10 into which the cotton is drawn by the picker needles, aided by said suction at the apertures 43 in the plate 44.

Manifestly, the construction as shown and described is capable of some modification and such

modification as may be construed to fall within the scope and meaning of the appended claims is also considered to be within the spirit and intent of the invention.

What is claimed is:

1. In a cotton picking machine of the type having opposed reciprocating banks of picking needles, a needle operating means comprising a helically grooved shank for said needle, a sleeve through which said needle shank reciprocates, a needle actuating arm to which said shank is connected, a collar arranged for limited sliding movement on said sleeve, means to effect movement of said collar, said collar having diametrically opposed ball recesses therein, balls in said recesses adapted upon movement of said collar in one direction to engage the grooves of said shank to rotate said shank and needle and means to effect reverse movement of said collar upon reverse movement of said needle to retract said balls from said grooves whereby they will be ineffectual to rotate said needle.

2. In a cotton picking machine having opposed groups of reciprocating picking needles, a needle and a needle operating means, said needle comprising axially aligned and connected sections, one section having barbs for the impalement of cotton when projected into a cotton bearing plant, the other and operating section having spiral grooves therein, an actuating bar for reciprocating said sections as a unit, a sleeve in which said operating section reciprocates, a collar slidable on said sleeve and having diametrically opposed ball recesses therein, balls in said recesses, and operated upon movement of said collar in one direction to engage in the grooves of said operating section to rotate said barbed section on the impaling thrust and means effective to retract said balls from said grooves whereby they will be rendered inoperative upon reverse movement of said collar to rotate said barbed section and means for doffing cotton impaled on said latter section.

3. In a cotton picking machine having opposed groups of reciprocating picking needles, a needle and an operating means therefor, said needle having a spirally grooved shank and a barbed section for impaling cotton when projected into a cotton bearing plant, a guard carried by the operative end of said barbed section, a station-

ary sleeve, a collar arranged for limited sliding movement on said sleeve, having ball recesses therein, balls in said recesses actuated by movement of said collar into the grooves of said shank upon the impaling thrust of said needle to effect rotation of the latter and means to retract said balls from said grooves whereby said balls will be rendered inoperative to rotate said needle upon the return movement thereof and means for doffing cotton from the barbed section of said needle upon its return movement.

4. In a cotton picking machine of the type employing rotating needle spindles, a series of groups of spirally grooved needle spindles, stationary sleeves for rotatably receiving said spindles, a collar mounted for limited sliding movement on each of said sleeves, ball recesses in said collar, balls in said recesses movable into the grooves of a spindle for imparting rotary movement thereto only upon the forward thrust thereof and means for reciprocating said spindles.

5. In a cotton picking machine of the type employing rotating needle spindles, a series of groups of spirally grooved needle spindles, a stationary sleeve rotatably receiving each of said spindles, balls retained for movement into the grooves of each spindle for imparting rotary movement thereto only upon the forward thrust thereof, means for retracting said balls from said grooves upon reverse movement of said spindle, guards carried by the operative end of the needles of said spindles and means for reciprocating said spindles.

6. In a cotton picking machine a series of spindles having spiral grooves therein and provided with barbed picking sections, grouped sleeves in which said spindles are operative, balls retained for movement into the grooves of each spindle for imparting rotary motion to said spindle and its barbed section in one direction only, means for withdrawing said balls from said grooves upon reverse movement of said spindle, means carried by the end of each barbed section to protect cotton stalk foliage from the effects of the barbs during the impaling thrust of said barbed section, means for reciprocating said spindles and means for doffing said barbed sections.

WILLIAM N. SMITH.
